PAUL A. A. ROUIS, OF BURLINGHAM, NEW YORK

EGG-PROTECTING MEANS

Application filed March 12, 1927. Serial No. 174,948.

This invention relates to a means for protecting eggs from being damaged by being frozen.

The invention has for its object the protection of eggs susceptible to temperatures at or below freezing, or in other words at or below 32° F., which causes damage to the eggs. In shipping eggs, it has been the custom to pack them in cases or crates. These 10 crates are of standard size and are adapted to contain thirty dozen. Hatching eggs particularly require protection during severe weather. Under the present custom, the eggs do not have the proper protection in cold 15 weather when the temperature is below 32° F. Express companies called upon to deliver the eggs, require additional protection than that afforded by the crate itself. The express companies have issued a notice to the effect, 20 that when temperature is 32° F., or freezing, the case or crate must be wrapped in at least one sheet of paper, and when the temperature is at 15° F. or below, a wrapping consisting of at least two sheets of paper must 25 be provided. To carry out the provisions of such requirement, it is contemplated, in accordance with the present invention, to provide a separate preformed insert or lining adapted to fit within the case or crate, one or 30 more of these inserts or linings being used according to the size and construction of the case or crate, in compliance with the requirement regarding the temperature range from 32° F. to 15° F. To comply with the 35 requirement as regards the temperatures below 15° F. there is provided a separate preformed outer cover or wrapper, which may be quickly and easily slipped over the case or crate to 40 completely enclose the same, in addition to the inserts or linings.

The objects of the present invention are attained by the means hereinafter fully described, and illustrated in the accompanying drawings, which is shown by way of example.

In the drawings—

Figure 1 is a perspective view of a crate protected in accordance with the present invention.

Fig. 2 is a perspective view illustrating the

top folds or sections of the outer protective cover opened; the inner protecting inserts or linings being shown in place within the crate, the top splints of which have been broken away.

Fig. 3 is a view of the blank from which the inner protective lining is formed.

Fig. 4 is a perspective view of the inner protective lining or insert ready for use.

Fig. 5 is a view of a blank from which the outer protective covering is formed.

Fig. 6 is a perspective view of the outer protective covering preformed ready for use.

The standard case or crate used for shipping eggs is of rectangular construction and 65 consists of end frames connected together by bottom, side, and top splints, there being cleats secured to the splints of each of the end frames, and a central partition being provided which divides the crate into two 70 compartments in which the eggs are packed, usually thirty dozen. Such crate appears in Fig. 2 and is designated 10.

In order to provide protective means for the eggs in compliance with the requirement 75 hereinbefore mentioned, that at least one thickness or sheet of material such as paper must be provided when the temperature is at 32° F., there is provided a preformed and separate insert or lining adapted to be 80 arranged in each of the compartments of the crate 10. Each of these inserts or linings is produced from a blank cut and formed from a single piece of material such as stout paper. The blank is illustrated in Fig. 3 and consists of a bottom 11, sides 12, top fold or section 13, flap 14 on opposite edges of each of two of the sides 12, a flap 15 on three of the sides 12, and the end portion 16 of the top fold or section 13 having imprinted thereon the word "Protected." The blank is folded along the dotted lines, and the flaps 14 of two of the sides 12 are pasted or otherwise attached to the other two sides 12. This provides a receptacle designated 17, as shown 90 most clearly in Fig. 4. The receptacle 17 constitutes an insert or lining, in that it is adapted to be inserted or arranged in one of the compartments of the crate 10. Since

the crate 10 has two compartments, two of 100

the receptacles 17 will be used. After the receptacles 17 are put in place within the compartments of the crate 10, the eggs are packed in the usual manner in the receptacle 17, whereupon, the flaps 15 are first brought over the top of the receptacle, and then the top fold or section 13 is brought over the top of the receptacle. The portion 16 having the word "Protected" is tacked to the upper cleat of the related end frame of the crate, as shown most clearly in Fig. 2. The word "Protected" denotes that the eggs are protected, which will be understood at a glance. The eggs are thus protected against cold, and 10 these receptacles or inserts serve adequately at a range of temperature from 32° to 15° F.

In order to provide additional protection for the eggs at temperatures below 15° F. there is provided an outer protective covering. This outer protective covering is produced from a blank cut and formed from 20 a single piece of material such as stout paper. This blank is illustrated in Fig. 5 and consists of a bottom 18, sides 19, ends 20, top sections or folds 21, flaps 22 at opposite edges of each of the sides 19, and flaps 23 at opposite edges of the top sections 21. The blank is folded on certain of the dotted lines so that the flaps 22 may be secured to the ends 20. This provides a preformed receptacle 24. The receptacle 24 constitutes an outer protective covering, and is adapted to be slipped over the crate 10, whereupon, the top sections or folds 21 are brought over the top 35 of the crate, and two of the flaps 23 are secured to the ends 20, and the other two flaps 23 are preferably tacked to the case 10. This outer covering may have printed on each of the sides 19 the word "Eggs" and on the one 40 of the top folds 21 the following "Eggs", "This side up—handle with care".

It is to be understood that to comply with the requirement as regards the range of temperature from 32° F. to 15° F., instead of 45 using two inner inserts or linings, the outer protective covering alone may be used to enclose the crate 10.

From the foregoing it will be apparent that there has been provided separate outer 50 and inner protective means adapted to be used in conjunction with a crate for the intended purpose, that this protective means may be quickly and easily put into use, since both the inner inserts or linings and the outer covering will be preformed. These inserts and the covering being made of material such as stout paper may be folded to a collapsed condition so that great quantities may be kept in a comparatively small 55 space. This is accomplished by folding the bottom and ends of the receptacles 17 and 24 inwardly along central and diagonal fold lines.

When the outer protective covering 24 is 60 used in conjunction with the inserts 17, the

portions 16 will extend below the lower edges of the flaps 23 respectively with the word "Protected" on the lowermost part of each of the portions 16 appearing to denote that the crate is protected, as shown most clearly in Fig. 1. When the inserts 17 are used without the protective covering, the portion 16 of each insert 17 is torn along the line of perforations 25, leaving but one word "Protected" appearing as shown in Fig. 2. If desired, instructions may be printed on the portions 16 as follows "Tear off when insert only is to be used."

I claim:

1. The combination with a crate adapted to contain eggs, of a separate preformed outer protective covering adapted to be arranged on said crate to completely enclose the crate and being removable from the crate, and a separate preformed inner protective lining adapted to lie contiguous the adjacent walls of the crate and to completely enclose the eggs and being removable from the crate, said inner lining having an indicia bearing flap capable of being attached to the upper edge of one of the walls of the crate, and exposed to view with the outer protective covering on the crate.

2. The combination with a crate adapted to contain eggs or other goods to be protected from a detrimental temperature, of a preformed inner protective lining which conforms to the shape defined by walls of the crate and so as to lie contiguous said walls, and also to completely enclose part of the 100 contents of the crate, said lining having means adapted to be affixed to the crate externally thereof, to indicate that the crate is protected.
